HANS WILLIG

By Richard M. Owen Attorney

UNITED STATES PATENT OFFICE.

HANS WILLIG, OF SANTA BARBARA, CALIFORNIA.

LATH NAIL.

Application filed July 25, 1925. Serial No. 46,077.

This invention relates to lath nails and has for its object the production of a simple and efficient means for fastening galvanized wire mesh to a support such as chicken wire 5 to constitute lathing material upon which plaster is adapted to be supported.

Another object of this invention is the production of a simple and efficient means for securely fastening the wire mesh lath 10 to the lathing nails and the support.

With these and other objects in view, this invention consists of certain novel construction, combinations and parts as will be hereinafter more fully described and claimed.

15 In the drawings:

Figure 1 is a side elevation of a lath nail, the support being shown in section.

Figure 2 is a section taken on line 2—2 of Figure 1.

20 Figure 3 is a section taken on line 3—3 of Figure 1.

Figure 4 is a perspective view of the lath nail and clamping means mounted thereon, and

25 Figure 5 is a vertical sectional view through the clamping sleeve.

By referring to the drawings, it will be seen that 1 designates the support of any suitable or desired construction, to which 30 the lath nail 2 is adapted to be secured. The lath nail 2 is provided with the usual head 3, and a clamping sleeve 4 is slidably mounted upon the nail 2. After the sleeve 4 has been placed upon the nail 2, the outer 35 or pointed end 5 is flattened, as indicated clearly in Figures 1 and 3, for the purpose of facilitating the entering of the nail into the wood-support 1, and also for preventing the sleeve 4 from accidentally slipping off of 40 the nail 2.

By particularly considering Figures 4 and 5 of the drawings, it will be seen that the sleeve 4 constitutes a thimble-like structure having a central aperture 6 formed therein 45 through which the nail 2 passes. The outer or upper end of the sleeve 4 is provided with three upwardly formed radially extending biting ribs 7 to constitute gripping points, these points 7 projecting longitudinally from the sleeve, being adapted to firmly grip the wire mesh plastic-supporting material 8 illustrated in Figure 1. The ribs 7, as shown in Figure 5, have their top edges

curved downwardly and inwardly, terminating flush with the top of the sleeve at 55 the edge of the nail passage 6. It should be understood that the wire mesh 8 is adapted to fit against the under face of the head 3 of the nail 2, and by driving the nail firmly into the support 1, it will be seen that the points or gripping ribs 7 will bite into and firmly engage the wire mesh 8, as is clearly illustrated in Figures 1 and 2, and firmly hold the wire mesh in engagement with the nail, and against accidental removal therefrom. In other words, a very efficient clamping and biting means have been produced between the biting ribs 7 and the inner face of the head 3 of the nail 2.

In practice it is preferable to employ a 70 6 penny nail in order to efficiently carry the weight of the plaster, and other wall surfacing means adapted to be supported thereby. By means of the special attaching feature of the sleeve 4, the wire mesh may be efficiently stretched over the desired surface which is to be plastered, and held in a tight condition for efficiently supporting the plastic material, such as plaster and the like.

It should be further understood that the nail 2, as well as the sleeve 4, are adapted to be galvanized in order to insure the same against rusting or becoming affected by the dampness in the walls upon which the nail 85 is used.

Having described the invention, what is claimed is:

1. The combination with a nail having a head, an elongated body and a flat penetrating tip, a sleeve slidably mounted on the body of the nail, and a series of radially extending spaced ribs formed upon the end of said sleeve adjacent the head and adapted to abut the underside of the same, said ribs having their top edges curved downwardly and inwardly to the center of said body, substantially as and for the purpose set forth, said sleeve being prevented from accidental removal from the nail body by means of the head and flat penetrating tip.

2. The combination with a nail having a head, an elongated body and a flat penetrating tip, of a sleeve slidably mounted on the nail, and a series of equally distantly spaced radially extending ribs formed upon the end

of said sleeve adjacent said nail head and adapted to abut the under side of said head, said ribs having their top edges curved downwardly and inwardly from the outer 5 end thereof to a point adjacent the center of the sleeve, the inner end of the ribs having their top edges terminating flush with

the top of the sleeve, said sleeve being prevented from becoming accidentally removed from the nail body by means of said head 10 and flat penetrating tip.

In testimony whereof I affix my signature.

HANS WILLIG.
